UNITED STATES PATENT OFFICE.

RICHARD GOLL, OF FRANKFORT-ON-THE-MAIN, GERMANY.

APPARATUS FOR EQUALIZING AIR-CURRENTS.

SPECIFICATION forming part of Letters Patent No. 681,215, dated August 27, 1901.

Application filed December 29, 1897. Serial No. 664,360. (No model.)

To all whom it may concern:

Be it known that I, RICHARD GOLL, manufacturer, residing at Frankfort-on-the-Main, in the Kingdom of Prussia, German Empire, have invented new and useful Improvements 5 in Apparatus for Equalizing Air-Currents, (patented in Germany, No. 84,471, dated July 29, 1893; in France, No. 248,661, dated July 4, 1893; in Austria, No. 46/470, dated January 18, 1896; in Hungary, No. 5,086, dated January 19, 1896; in Switzerland, No. 12,713, dated January 18, 1896, and in Italy, No. 31/40,680, dated March 3, 1896,) of which the following is a specification.

15 The object of my invention is to obviate the drawbacks inherent to the actual systems of distributing the air and to regulate its current when used for the ventilation of rooms or the supply of furnaces and the like. The 20 air has always the tendency to go from its entrance into a room or chamber on the shortest way to the point where an opening for the escape of it is provided, especially if the air enters under pressure or escapes by suction. 25 Even in cases wherein a conduit for the admission or the escape of the air is divided into different branches leading to different points of one room, this inconvenience is not sufficiently diminished, because the openings 30 of the branch pipes or conduits placed in the neighborhood of the main conduit will on account of their shortness and smaller friction convey more air than the openings at more distant points. The same drawback is re- 35 marked in furnaces, wherein the air enters under the grate on a broad area, passes the grate, goes over the bridge, and then into the chimney, the direction of the current being bent at different places. In this instance the 40 maximum current will follow a line which approaches a straight line as nearly as the obstacles put in the way of it will allow. The supply of the air to the points distant of this line will be smaller. This is true for the 45 points situated in the immediate neighborhood of the grate, where an equal supply of air to all points in the fuel is wanted. I propose to remedy this by shaping the conduits in connection with the distant points of a 50 room in a way that their lengths are equal and attain this by curving or otherwise bend-

ing the conduits leading to the nearer points. In cases where the stream of air is not divided into different films or branches I provide partition-walls or the like, forming conduits of equal length between themselves. This is especially the case if my invention is applied to fire-grates. As the air has the tendency to stream in a straight line from the door of the ash-pit to the back part of the 60 grate and the edge of the fire-bridge and therefrom obliquely upward to foot of the chimney, I lengthen the ways of the air passing at the back part of the grate, and thereby attain a perfectly equalized draft in the plane 65 of combustion.

In order to show the manner in which I carry my invention out, I have affixed drawings.

Figure 1 shows the ventilation of a room; 70 Fig. 2, a construction of a grate and flues under a boiler; Fig. 3, another construction for the same purpose.

Fig. 1 is a plan of the ceiling of a room, wherein conduits for the escape of the air are 75 provided. H is the chimney or main channel leading the spent air into the open air. a b c d are openings in the ceiling connected by pipes A B C D with the channel H, the pipes B A D being curved to attain exactly or 80 approximately the length of the pipe C.

In Fig. 2, A' represents the grate; B', the entrance-opening for the combustion-air in the ash-pit; b, the fire-bridge; m and n, partition-walls built to divide and conduct the com- 85 bustion-gases. The current of the combustion-gases is split into three branches q r s, following the arrows 1 2 3. Without the partition-walls the suction exercised by the chimney would prove strongest for the part s of 90 the gases, and therefore the speed of these gases would be the greatest and their quantity the largest. By curving the current s downward its way is lengthened and the impetus given to it lowered to the same degree 95 as imparted to the currents q and r. This equalization provides for the inequality caused by the conditions back of the grate.

Fig. 3 shows a device providing for the inequality caused by the easier afflux of the air 100 to the parts of the grate near the entrance of the air into the ash-chamber. The door B is

held closed and the air admitted by a conduit C'. Here the current of the air is split in the same manner, and the paths leading from the mouth c' of the conduit to the different parts of the grate are rendered approximately equal in length.

The system of ventilation shown in Fig. 1 may be especially advantageously applied if the conduits consist of rubber tubes allowing to displace the entrance or discharge openings.

It will be seen that the passage which leads from the part of the room or chamber farthest from the outlet, as C, Fig. 1, or q, Fig. 2, is straight, and that the extent of bend of the other passages increases with the nearness to the outlet of the inlet ends of said passages, thereby equalizing the lengths of the passages.

Now what I claim, and desire to secure by 20 Letters Patent, is the following:

The combination with a chamber having a suitable outlet through which air is to be passed from the chamber, of a plurality of passages from points at different distances 25 from the outlet, the passages from points nearer the outlet being bent to a greater or less extent to increase their length to equal that of the passage from the most distant point to the outlet, the latter passage being 30 substantially straight.

In testimony whereof I have signed my name to this specification in the presence of two subscribing witnesses.

RICHARD GOLL.
